UNITED STATES PATENT OFFICE.

ALFRED D. ANTOINE, OF CHICAGO, ILLINOIS, ASSIGNOR TO ADVANCE MACHINE COMPANY, OF CHICAGO, ILLINOIS, A CORPORATION OF ILLINOIS.

CHECK-CONTROLLED MACHINE.

Application filed March 28, 1921. Serial No. 456,109.

To all whom it may concern:

Be it known that I, ALFRED D. ANTOINE, a citizen of the United States, residing at Chicago, in the county of Cook and State 5 of Illinois, have invented certain new and useful Improvements in Check-Controlled Machines, of which the following is a specification.

This invention relates to improvements in 10 check controlled machines, and one of the objects of the invention is to provide an improved device of this character which will receive a coin of a predetermined denomination and permit the same to move into an 15 operative position with respect to the coin actuated mechanism, but which will arrest improper checks and prevent the same from actuating the mechanism which it is necessary to actuate by a check.

20 A further object is to provide an improved device of this character embodying a receptacle for delivering a commodity, and improved means for rendering the receptacle active and inactive with respect to the 25 check controlled mechanism, whereby the receptacle will not be actuated until a proper check is inserted.

To the attainment of these ends and the 30 accomplishment of other new and useful objects as will appear, the invention consists in the features of novelty in substantially the construction, combination and arrangement of the several parts hereinafter more 35 fully described and claimed and shown in the accompanying drawings illustrating this invention and in which—

Figure 1 is a front elevation.

Figure 2 is an enlarged detail sectional view taken on line 2—2, Figure 11.

40 Figure 3 is an elevation of a detail.

Figure 4 is a vertical sectional view taken on line 4—4, Figure 1.

Figure 5 is a view taken on line 5—5, Figure 4.

45 Figure 6 is a sectional view taken on line 6—6, Figure 11 with parts omitted and parts in elevation.

Figure 7 is a sectional view taken on line 7—7, Figure 11 with parts omitted, parts in elevation, and parts in adjusted positions.

50 Figure 8 is a view similar to Figure 7 showing the parts in a different position.

Figure 9 is a view similar to Figure 5

showing the check carrier in position to deliver a check therefrom.

55

Figure 10 is a view similar to Figure 9 with the parts in a different position.

Figure 11 is a sectional view taken on line 11—11, Figure 1.

Figure 12 is a detail view of the ratchet 60 disc, operating dog and retaining pawl in their normal positions.

Referring more particularly to the drawings the numeral 15 designates a face plate which may be of any desired size and configuration and is preferably constructed of sheet material bent into shape and provided with an opening 16 at one edge thereof into which the check or coin is adapted to be inserted. Secured to the back of the 70 plate 15, are spacing members 17—18, which are respectively shaped to form shoulders 19—20, for a purpose to be hereinafter set forth.

A supporting plate 21, is arranged adjacent these members 17—18, and the parts are held together in any desired or suitable manner such as by means of supporting posts 22, and fastening bolts 23, which are secured to the plate 15, and pass through the 80 members 17—18 and also the supporting plate 21.

Operating between the plates or members 21 and 15, is a check carrying disc 24, which is provided with a check receiving portion 85 or seat 25, opening through the periphery of the disc. This disc is rotatably held in position preferably by means of a handle 26, which passes through a suitable opening in the front plate 15, and which opening is 90 preferably provided with a flange 27 therebeyond to form a bearing in the handle. The rear portion of the handle is reduced as at 28, for a purpose to be hereinafter set forth, and the reduced portion is provided with a flattened surface 29. The reduced portion 28, of the handle passes through an opening in the check carrying disc 24, which opening is of a size and configuration to conform to the reduced portion 28 of the 100 handle so that when the handle is passed through the opening in the check carrying disc 24, the latter will rotate with the handle.

This disc 24, is provided with a cam shaped projecting portion 30, extending 105 from the periphery thereof, and one edge

of the cam is adapted to engage the shoulder 19, of the member 17, when the disc is rotated in one direction, to limit its movement in that direction, and the other edge of the cam shaped portion 30, engages the shoulder 20 of the member 18, to limit the rotation of the disc 24 in the opposite direction. The disc is also provided with notches 31-32, through its periphery for a purpose to be 10 hereinafter set forth.

Disposed intermediate the member 15 and the member 21, is a check receiving support 33, which is provided with an inclined or beveled surface 34, upon which the check 15 is adapted to rest when it is delivered from the check seat 25, of the disc 24.

The member 21 is provided with a depressed or recessed portion 35, which stands adjacent the inlet opening 16 to form a 20 pocket for receiving the check and directing the same into the check seat 25, of the disc 24. Supported by the member 21, is a catch 36, which may be of any desired size and configuration. This catch is preferably held 25 in position by means of a fastening bolt 37, which passes through a suitable bearing 38, and has a reduced extremity 39, that passes through a suitable aperture in the catch. The catch preferably arches over a bearing 30 40, carried by the member 21, and through which bearing the reduced end 28, of the handle 26, passes. The free extremity of the catch 36 is provided with an offset portion 41, having a beveled surface and which portion 45 passes through a suitable opening 42 in the member 21, and this offset portion is adapted to enter the notches 31-32 of the check carrier 24, when the notches are disposed opposite the offset portion. The 40 offset portion 41, of the catch 36 normally assumes a position to enter these notches when the check carrier is rotated, and to that end there may be provided a spring 43, one end of which is anchored to the catch 45, and the other end to a stationary member 44. The catch 36 is also provided with an offset portion 45, which is adapted to project into the check seat 25 of the disc 24, when the latter is rotated and when no check is carried 50 in the check seat 25. The spring 43 tending to move the catch 36, in a direction to cause the projection 45 to enter the check seat, will cause the offset portion 41 to assume a position in one of the notches 31-32 and thereby lock the check carrier against rotation beyond a predetermined degree of movement. When a check of a proper denomination is placed within the check seat 25, and when the disc 24 is rotated with the 60 check in the seat, the check will engage the projection 45, to shift the catch 36, laterally so as to move the offset portion 41 laterally away from the disc 24, and against the stress of the spring 43, and thereby permit the 65 check carrier to be rotated to the full extent

of its movement or until one edge of the cam shaped portion 30 engages the shoulder 19. When the check carrier is rotated in the opposite direction the other edge of the cam shaped portion 30 will engage the shoulder 20 and limit its rotation in that direction, and the shoulder 20 will serve to position the check seat 25 to receive a check.

In the event that a washer or an apertured check is placed within the check seat, the 75 projection 45, will enter the opening in the washer and the spring 43 will then move the catch 36 in a direction so that the offset portion 41, will engage one of the notches 31-32, and thereby lock the check carrier 80 24 against further rotation and will prevent the delivery of the bogus check or washer from the check seat. The beveled surface of the projection 41 will however permit the disc 24 to be turned backwards after the 85 projection enters either of the notches 31 or 32.

The reduced extremity 28, of the handle 26, projects into an element 46, which is preferably cup shaped, through an opening 90 which is irregular in cross section and which fits upon the handle so as to rotate with the handle, and this member 46 is secured to the handle for rotation therewith in any suitable manner such as by means of a fastening nut 95 or collar 47, which is preferably screwed upon the end of the handle and if desired a washer 48 may be interposed between the member 46 and the collar 47.

Connected with the element 46 and preferably by one end thereof is a spring 49, the free end of which is anchored to any suitable fixed support. This spring 49 tends normally to rotate the handle 26 and the check carrying disc 24 in one direction and 105 to normally maintain the check seat 25, of the disc 24 in alignment with the check receiving opening 16 or, in the position of the disc shown in Figure 5.

When the check is inserted in the check 110 seat and the handle 26 rotated, to rotate the disc 24, the element 46, will be rotated with the handle and the end of the spring 49 will be wound upon the periphery of the element 46, as shown in Figure 8 so that, when the 115 handle 26 is released the spring 49 will tend to move the disc 24 back to its normal position or to the position shown in Figure 5.

The element 46 is preferably provided with an arm or projection 50, see particularly Figure 11, and which projection carries a lug 51 extending laterally therefrom. Pivotally mounted upon this lug 51, is a dog 52 provided with an arm 53, having a lateral projection 54 at one extremity thereof and a cam shaped portion 55 on the other end thereof. This dog 52 is adapted to swing freely upon the lug 51, and a spring 56 is anchored by one extremity to the dog and by its other extremity preferably to the ele- 125 130

ment 46 so that when the element 46 is rotated by the handle 26 to move the dog 52 bodily, the spring 56 will move therewith and at all times the normal tendency of this 5 spring is to move the projection 54 inwardly toward the lug and the cam shaped portion 55 of the dog outwardly away from the lug for a purpose to be set forth.

Loosely mounted upon the extremity 57 of 10 the handle 26, is a disc 58, provided with a notch or cut away portion 59 in its periphery and a series of teeth forming shoulders 60, 61 and 62. The disc is also provided with a recessed portion 63, adjacent the shoulder 15 62. This disc is provided with a boss or projection 64 having an opening 65 therein and a flattened portion 66 forming one of the walls of the opening. The disc is free to rotate upon the end 57 of the handle 26, and 20 is adapted to be rotated with the handle by means of the dog 52. That is, when the lateral projection 54 of the dog 52 enters the recess 59, the projection 54 will engage one of the shoulders of the recess so that when 25 the handle 26 is turned the disc 58 will be rotated and when the handle is released, while the projection 54 is in the recess 59, the spring 49 will cause the dog 52 to operate upon the disc 58, and rotate it in the opposite 30 direction.

Co-operating with the disc 58 is a dog 67 pivotally mounted as at 68, preferably upon the member 21. This dog is provided with a projection 69 that is adapted to engage 35 and move about the periphery of the disc 58, and also to co-operate with the shoulders 60, 61 and 62, in a manner to be hereinafter set forth. A spring 70 is connected by one end with the dog 67, and is 40 anchored as at 71, to a suitable fixed support. The spring is so arranged that it normally exerts its stress upon the dog 67, in such a manner as to tend to move the projection 69 on the dog against the periphery 45 of the disc 58, and to hold the same thereagainst so that, as the disc 58 is rotated in a manner as already set forth, and under certain conditions, the projection 69 will successively engage the shoulders 60, 61 and 50 62, and maintain the disc against a retrograde movement when the projection 69 is engaged with one of the shoulders.

This dog 67 is provided with a lateral projecting portion 72, which stands adjacent but is spaced from the inclined or beveled surface 34, of the element 33, and the proximate face of the projection 72 is preferably notched or cut away as at 73, so as to receive the edge of the token or check 74. 55 The projection 72 is so disposed with respect to the surface 34 that the spring 70 will tend normally to move the projection in a direction towards the surface 34, the movement of the projection towards the surface 60 being arrested by the projection 69 on the

dog 67, engaging the periphery of the disc 58. The space between the projection 72 and the surface 34 is such that it is somewhat less than the diameter of the proper check or token so that when a token is delivered from the check seat 25, as shown in Figure 9, it will engage the surface 34 and project into the notch 73, of the projection 72. When a check is thus delivered from the check seat 25, as shown in Figure 9, and 75 when the disc 24 is released or turned in a backward direction, one of the walls of the check seat 25, engages the periphery of the token and forces it between the surface 34 and the projection 72, with the result that 80 the dog 67, will be rocked about its pivot 68 against the stress of the spring 70, and will move the projection 69, on the dog away from the periphery of the disc 58, and thereby allow the disc 58 to be rotated 85 when the check carrying disc 24 is returned. The token 74 will be held frictionally in position between the surface 34 and the projection 72, after passing out of the check seat 25, until the token is engaged by the 90 cam or projection 30, on the disc 24 as shown in Figure 10. The engagement of the cam or projection 30 of the disc 24, with the token 74 will force the latter between the surface 34 and the projection 72, and the 95 token will then be delivered into a suitable receptacle provided for receiving the same. After the token disengages the projection 72, the spring 70 will cause the projection 69 on the dog 67, to move toward the periphery of the disc 58. 100

If desired, a magnet 75 may be arranged adjacent the path of movement of the token 74, by the check carrying disc 24. When provided this magnet operates upon metallic 105 checks or tokens to maintain the same within the check seat 25 so that if an improper token is deposited in the check seat, it will not be delivered from the check seat to operate the dog 67, and the check or token will 110 remain in the check seat and will be brought back to the entrance opening 16, through which it may be readily removed.

Supported in any suitable manner, in the rear of the disc 58, is a casing 76, having 115 an entrance opening 77, for the commodity to be dispensed and a delivery outlet opening 78, which delivery outlet discharges into a suitable chamber 79, having an open front through which the articles may be removed. A pivotally supported closure 80 is arranged across the delivery opening 78, and this closure is controlled by means of a suitable weight 81, the weight tending normally to hold the closure 80 against the outlet opening 78. Depending from the closure 80 is a projection 82, which is adapted to be engaged by the fingers of the operator so that when the commodity is delivered upon the closure 80, the operator by inserting his 120

125 130

hand into the opening of the chamber 79, so that the ends of the fingers will engage the projection 82, with the palm uppermost, will rock the closure 80, and the commodity supported by the closure will be deposited into the hand of the operator.

Within the chamber 76 is a drum like element 83, having a trunnion 84, which is journaled in one wall of the casing and a trunnion 85, journaled in the other wall of the casing. This drum like element 83 is provided with a chamber 86, that is adapted to receive the commodity that is delivered thereto through the opening 77, when the chamber 86 is in register therewith but when the drum like element 83 is rotated so as to move the chamber 86 out of communication with the opening 76, the periphery of the drum like element will close the opening, at which time the chamber 86 will be adapted to assume a position to empty the contents thereof upon the closure 82.

The trunnion 85 is provided with a flattened portion 87, see particularly Figure 11, so that when the trunnion projects into the opening 65 of the hub 64 of the disc 58, the two will be connected together for simultaneous rotation, so that the drum like element 83 will be rotated through the medium of the rotation of the disc 58, in the manner as already set forth, and when the disc 58 is held against rotation, the drum like element 83 will also be held against rotation.

If desired and to permit the projection 45 on the catch 36 to move out of the check seat 25, when the disc 24 is rotated in a direction to return the check seat to the opening 16, without engaging the wall of the check seat and thereby locking the disc 24 against rotation, the disc 24, may be provided with a beveled or suitable shaped portion 88 adjacent the wall of the check seat, as shown more clearly in Figure 5. It is thought that the operation of this device will be clearly understood from the foregoing, but briefly stated it is as follows:

The normal position of the check carrier is shown in Figure 5, at which time the ratchet disc 58, operating dog 52 and the pawl 67 will be in the positions shown in Figure 12. At the same time, the drum like element 83 will be in the position shown in Figure 2, that is with the receptacle or chamber 86 therein in the position to receive a supply of the commodity to be dispensed.

In the event that the handle 26 is rotated with the parts in this position, the disc 58 will be held against rotation by reason of the fact that the projection 69 on the dog 67, is seated in the recess 63, and the dog 52 will be moved with the handle so that the projection 54 on the dog will ride over the periphery of the disc 58, and the drum like element 83 will be held against rotation. In

this position the check carrying disc 24 is adapted for a forward and backward movement and the extent of the forward movement of the disc 24 will be limited by the projection 41 on the catch 36 entering the notch or recess 32 in the periphery of the check carrying disc 24, while the return or retrograde movement of the disc 24 will be limited by the edge of the cam shaped projection 30, of the disc engaging the shoulder 20, shown in Figures 9 and 10.

Should a washer be inserted in the check seat 25, and the disc 24 advanced the projection 45 on the catch 36 will enter the opening in the washer and permit the projection 41 to enter one of the recesses 31-32 in the disc 24 as the latter is rotated and arrest its rotation.

During the rotation of the disc 24 under these two conditions the projection 54 on the dog 52, will be held against entering the recess 59 of the disc 58, when it stands adjacent the recess, by means of the cam shaped portion 55 of the dog 52, by reason of the fact that this cam shaped portion 55 will engage and ride over the projection 69 on the dog 67, and will hold the projection 54 on the dog 52 in an inoperative position with respect to the disc 58.

If a check or token of an improper size in diameter is deposited in the check receiving opening 16, it will be carried by the check seat 25 of the disc 24 into the position shown in Figure 9, at which time the check will be delivered from the check seat 25 upon the support 34, and as the diameter of the check would be less than the space between the support 34 and the projection 72 of the dog 67, the check will fall from the check seat and be delivered into the machine, without shifting the dog 67 to release the disc 58.

Should, however, a proper check or token be deposited in the check seat, it will be carried by the disc 24 past the projection 45 on the catch 36 to shift the latter and hold the projection 41 on the catch in a position that it would not enter either of the recesses 31-32, but will be carried by the check carrier into the position shown in Figure 9, where it will be deposited upon the support 34 and will engage the support 34 and the projection 72 of the dog 67. Under these conditions, when a return or retrograde movement is imparted to the disc 24, the edge of the check seat 25 will engage the edge of the check 74 and force the latter into a position between the support 34 and the projection 72 of the dog 67 a sufficient distance to shift the dog 67 and move the projection 69 out of the recess 63, thereby releasing the disc 58. This releasing movement of the dog 67 will permit the spring 56 to shift the dog 52 so as to seat the projection 54 on the dog 52 in the recess 59, this operation being permitted by rea-

son of the fact that by that time the cam shaped projection 55 will disengage the projection 69 on the dog 67, thereby allowing the projection 54 to assume an operative position with respect to the disc 58. The disc 58 will then be locked for rotation with the handle 26, and as the disc 58 is locked with the drum like element 83, it will be manifest that as the disc 24 is returned, the element 83 will be rotated and deliver the commodity from the chamber 86. During this return movement of the check carrier 24 and the movement of the disc 58, the check 74 will be ejected from between the projection 72 on the dog 67 and the support 34 by the cam shaped projection 30 on the disc 24 (see particularly Figure 10), which engages the edge of the check and forces it from the support 34. When the check is thus released, which will occur at a time just after the cam shaped projection 55 has passed from the projection 69 of the dog 67, the projection 69 will under the influence of the spring 70, move against the periphery of the disc 58, so that after the check is ejected and the commodity delivered, and in the event that the handle 26 and check carrier 24 is again rotated in a forward direction, the disc 58, although it will be carried forwardly with the handle in this second operation, will be locked against return movement by reason of the fact that the spring 70 will cause the projection 69 to engage and ratchet across the shoulders 60, 61 and 62, until the recess 63 is positioned adjacent the projection 69 to receive the latter. The movement of the projection 69 into the recess 63 will, through the medium of the cam shaped portion 55 of the dog 52, shift the latter to move the projection 54 of the dog 52 out of the recess 59, and thereby unlock the disc 58 with respect to the handle 26, and the dog 67 will maintain the disc 58 and the drum like element 83 against rotation. The handle 26 and check carrier 24, may then be rotated forwardly and backwardly in the same manner as when there is no check inserted, that is the forward movement will be arrested by the projection 41 of the catch 36 entering one of the recesses 31-32, and the rearward movement will be arrested by the edge of the cam shaped portion 30 of the disc 24 engaging the shoulder 20. When the disc 58 is unlocked so that the handle may turn the disc as well as the drum like element 83, the forward movement of these parts will be arrested by reason of the edge of the cam shaped projection 30 of the check carrying disc 24 engaging the shoulder 19 (see particularly Figure 10.)

If desired a magnet 75 may be employed for preventing the delivery of a metallic check from the seat 25 of the check carrying disc 24.

If desired, an element 89 (see particularly Figure 4) may be provided which is adapted to rest against the supporting posts 22 and be secured thereto. This element may be provided with a flanged portion 90, adapted to project over the parts between the element 89 and the supporting plate 21 to prevent the insertion of any implement into the parts and this element 89 may be provided with an opening having a flange 91 around the opening to form a bearing for the hub 64 of the disc 58.

Obviously the casing 76 as well as the element 89 may be removably secured in position to permit their detachment when desired, so that access to the mechanism may be readily had.

The notch 73 in the projection 72, serves a further function of permitting thin checks or tokens to drop off of the check support 34 without shifting the projection 72, to render the ratchet element 67 inactive.

What is claimed as new is:—

1. Check controlled mechanism embodying a check carrier having a forward and backward movement, a rotatable ratchet disc, a ratchet element co-operating with the disc for maintaining the latter in its adjusted position, a check support for receiving the check from the carrier, a portion of the said ratchet element co-operating with the said seat and spaced therefrom a distance less than the diameter of the check, a portion of the check carrier operating on its retrograde movement to force the check between the said seat and the said portion of the ratchet element to shift the latter to release the disc, and means operating upon the disc when the latter is released to rotate the same with the check carrier, another portion of the check carrier operating upon the check to force the check from the support to release the said ratchet element to permit the latter to become active with respect to the said disc.

2. Check controlled mechanism embodying a check carrier having a forward and backward movement, a rotatable ratchet disc, a ratchet element co-operating with the disc for maintaining the latter in its adjusted position, a check support for receiving the check from the carrier, a portion of the said ratchet element co-operating with the said seat and spaced therefrom a distance less than the diameter of the check, a portion of the check carrier operating on its retrograde movement to force the check between the said seat and the said portion of the ratchet element to shift the latter to release the disc, means operating upon the disc when the latter is released to rotate the same with the check carrier, another portion of the check carrier operating upon the check to force the check from the support to release the said ratchet ele-

ment to permit the latter to become active with respect to the said disc, and means whereby the first recited means will be rendered inactive when the said ratchet 5 element is active.

3. Check controlled mechanism embodying a check carrier having a forward and backward movement, a rotatable ratchet disc, a ratchet element co-operating with the 10 disc for maintaining the latter in its adjusted position, a check support for receiving the check from the carrier, a portion of the said ratchet element co-operating with the said seat and spaced therefrom a distance 15 less than the diameter of the check, a portion of the check carrier operating on its retrograde movement to force the check between the said seat and the said portion of the ratchet element to shift the latter to release 20 the disc, means operating upon the disc when the latter is released to rotate the same with the check carrier, another portion of the check carrier operating upon the check to force the check from the support to release 25 the said ratchet element to permit the latter to become active with respect to the said disc, and means operatively connected with the first recited means and adapted to be shifted by the said ratchet element when 30 the latter is active to render the first recited means inactive.

4. Check controlled mechanism embodying a check carrier having a forward and backward movement, a rotatable ratchet 35 disc, a ratchet element co-operating with the disc for maintaining the latter in its adjusted position, a check support for receiving the check from the carrier, a portion of the said ratchet element co-operating with the 40 said seat and spaced therefrom a distance less than the diameter of the check, a portion of the check carrier operating on its retrograde movement to force the check between the said seat and the said portion of the 45 ratchet element to shift the latter to release the disc, means operating upon the disc when the latter is released to rotate the same with the check carrier, another portion of the check carrier operating upon the check to 50 force the check from the support to release the said ratchet element to permit the latter to become active with respect to the said disc, the said means embodying a dog, and a cam surface connected with the dog and 55 adapted to engage and be shifted by a portion of the ratchet element when the latter is active to render the first said means inactive.

5. Check controlled mechanism embodying a check carrier having a forward and backward movement, a ratchet disc, a dog movable with the said check carrier and co-operating with the said disc for moving the same forwardly and backwardly, a ratchet 60 element for maintaining the disc in its ad-

justed position, means whereby the said ratchet element will maintain the said dog inactive in the absence of a proper check in the check carrier, a check support for receiving the check from the check carrier, and 70 means whereby a movement of the check upon the check support will render the said ratchet element inactive, such movement of the ratchet element permitting the said dog to become active with respect to the disc to move the same.

6. Check controlled mechanism embodying a check carrier having a forward and backward movement, a ratchet disc, a dog movable with the said check carrier and co-operating with the said disc for moving the same forwardly and backwardly, a ratchet element for maintaining the disc in its adjusted position, means whereby the said ratchet element will maintain the said dog 80 inactive in the absence of a proper check in the check carrier, a check support for receiving the check from the check carrier, and means whereby a movement of the check upon the check support will render the said 85 ratchet element inactive, such movement of the ratchet element permitting the said dog to become active with respect to the disc to move the same, the said movement of the check being imparted thereto by a portion 90 of the check carrier.

7. Check controlled mechanism embodying a check carrier having a forward and backward movement, a ratchet disc, a dog movable with the said check carrier and co-operating with the said disc for moving the same forwardly and backwardly, a ratchet element for maintaining the disc in its adjusted position, means whereby the said ratchet element will maintain the said dog 100 inactive in the absence of a proper check in the check carrier, a check support for receiving the check from the check carrier, means whereby a movement of the check upon the check support will render the said ratchet 105 element inactive, such movement of the ratchet element permitting the said dog to become active with respect to the disc to move the same, the said movement of the check being imparted thereto by a portion 110 of the check carrier, and means operatively related to the check carrier for ejecting the check to render the said ratchet element active.

8. Check controlled mechanism embodying a check carrier having a forward and backward movement, a ratchet disc adapted for a forward and backward movement, a spring controlled dog operatively connected with the check carrier and co-operating 120 with the disc for moving the latter, a ratchet element for retaining the disc against movement, a check support for receiving the check from the carrier, means whereby a movement of the check upon the said sup- 125 130

- port will shift the ratchet element to render the same inactive, and means operatively connected with the said dog and adapted to engage and move over a portion of the said ratchet element whereby the said dog will be rendered inactive in the absence of a proper check in the check carrier.
9. Check controlled mechanism embodying a check carrier having a forward and backward movement, a ratchet disc adapted for forward and backward movement, a dog operatively connected with the check carrier for moving the said disc, a spring controlled ratchet element for maintaining the disc against operation, a check support for receiving the check from the check carrier, there being a projection connected with the said ratchet element, said projection co-operating with and spaced from the check support to form a check delivery opening, through which the check is adapted to be forced to render the said ratchet element inactive, the said dog and the said ratchet element being one rendered active when the other is rendered inactive.
10. Check controlled mechanism embodying a check carrier having a forward and backward movement, a ratchet disc adapted for a forward and backward movement, a spring controlled dog operatively connected with the check carrier for moving the said disc, a spring controlled ratchet element for restraining the disc, means whereby the check when it is delivered from the check carrier will actuate the said ratchet element to render the latter inactive, and means whereby the said ratchet element will control the operation of the said dog, the last recited means embodying a surface connected with the said dog and adapted to engage a portion of the said ratchet element when the latter is active to render the dog inactive.
11. Check controlled mechanism embodying a check carrier having a forward and backward movement, a ratchet disc adapted for a forward and backward movement, a spring controlled dog operatively connected with the check carrier for moving the said disc, a spring controlled ratchet element for restraining the disc, means whereby the check when it is delivered from the check carrier will actuate the said ratchet element to render the latter inactive, and means whereby the said ratchet element will control the operation of the said dog, the last recited means embodying a surface connected with the said dog and adapted to engage a portion of the said ratchet element when the latter is active to render the dog inactive.
12. Check controlled mechanism embodying a check carrier having a forward and backward movement, there being a projection on the carrier, spaced stops adapted to be engaged by the projection to limit the movements of the check carrier, a ratchet disc adapted for a forward and backward movement, a dog connected with the check carrier for moving the disc, a ratchet element for restraining the disc, a check support for receiving the check from the carrier, and means connected with the ratchet element and adapted to be shifted by the movement of the check upon the support to render the ratchet element inactive, the said projection being adapted to engage and move the check upon the said support.
13. Check controlled mechanism embodying a check carrier having a forward and backward movement, there being a projection on the carrier, spaced stops adapted to be engaged by the projection to limit the movements of the check carrier, a ratchet disc adapted for a forward and backward movement, a dog connected with the check carrier for moving the disc, a ratchet element for restraining the disc, a check support for receiving the check from the carrier, and means connected with the ratchet element and adapted to be shifted by the movement of the check upon the support to render the ratchet element inactive, the said projection being adapted to engage and move the check upon the said support, the said means embodying a projection co-operating with the said check support, the last said projection having a recessed or notched surface in proximity to the check support to permit the free passage of thin checks from the check support.

In testimony whereof I have signed my name to this specification, on this 25th day of March, A. D. 1921.

ALFRED D. ANTOINE.
